UNITED STATES PATENT OFFICE.

CHARLES FRANK BEAN, OF PORT TAMPA CITY, FLORIDA.

ADJUSTABLE SWING.

No. 857,432.

Specification of Letters Patent.

Patented June 18, 1907.

Application filed September 26, 1906. Serial No. 336,259.

To all whom it may concern:

Be it known that I, CHARLES FRANK BEAN, a citizen of the United States, and a resident of Port Tampa City, in the county of Hillsboro and State of Florida, have invented a new and Improved Adjustable Swing, of which the following is a full, clear, and exact description.

My invention relates to swings, and admits of general use, but is of peculiar value in relation to swings used for recreation and comfort, and in which an oscillatory motion is accompanied by a tilting motion.

My invention further relates to certain adjusting devices, whereby the character and degree of the tilting motion may be varied at will.

While my swing may be made in various forms, I show for convenience only a single typical form, to wit: a supporting frame and platforms depending therefrom, and provided with seats, together with means for adjusting these platforms and thereby causing the seats to tilt in different directions and to different extents, as desired.

Reference is to be had to the accompanying drawings forming a part of this specification, in which similar characters of reference indicate corresponding parts in all the figures.

Figure 1 is a vertical section through the improved swing, showing the hand wheels and connections for adjusting the platforms 20, 21; Fig. 2 is a vertical cross section through the swing upon the line 2—2 of Fig. 1, looking in the direction of the arrow, and showing the arrangement of the racks, pinions and the means for turning the pinions in order to effect the several adjustments; Fig. 3 is an inverted plan or bottom view of the mechanism shown in Fig. 2; Fig. 4 is a diagram showing the platforms 20, 21 tilted when the adjusting shafts 30, 43, 53 and 40^a are in such position as to cause the platforms 20, 21 to assume the tilting movement indicated; Fig. 5 is a diagram of the same mechanism and showing the adjusting shafts so arranged as to maintain the platforms 20, 21 horizontal at all times during the swinging motion; and Fig. 6 is a diagram showing the parts so adjusted as to cause the platforms 20, 21 to tilt in the direction opposite to those indicated in Fig. 4, and also to increase the extent of this tilting movement.

A number of uprights 7 are connected together by braces 8, 9 and beams 10, 11, so as to form a rigid frame. Mounted upon this

frame are cross rods 12, 13, 14, 15 from which hang suspenders 16, 17, 18, 19, each having the form of a flattened bar and which may be made of wood or metal, as desired. Supported by the suspenders 16, 17 is a platform 20, and similarly supported by the suspenders 18, 19 is a platform 21. These platforms are connected together by a platform link 22 connected therewith by hinges 23. Seats 24, 25 are mounted upon the platforms 20, 21. A strap 26 is connected rigidly with the platform 20 and within this strap and parallel with the platform 20 are racks 27 of metal. Meshing with each rack is a pinion 28, and these pinions together with rollers 29 are mounted upon opposite ends of an adjusting shaft 30. When this shaft is caused to rotate, the pinions 28 move bodily along the racks 27, the rollers 29 merely moving slidably along the strap 26. A bearing 31 is connected with the adjusting shaft 30 and is threaded so as to fit upon a threaded shaft 32. One end of this shaft is mounted within a bearing 33 which is fixed relatively to the platform 20. The shaft 32 is further provided with a bevel gear 34 which meshes with another bevel gear 35, the latter being mounted upon the lower end of a vertical shaft 36 provided at its upper end with a hand wheel 37. By turning the hand wheel 37 the operator causes the rotation of the gear wheels 35, 34 and the threaded shaft 32, thereby drawing the bearing 31 and its accompanying parts backward or forward according to the direction of movement of the hand wheel 37. This causes the suspenders 16 to be drawn toward the center of the platform 20 or to be pressed away from the center according to the direction of movement of the hand wheel 37. Another hand wheel 38 is mounted upon one of the suspenders 17 and is adapted to communicate motion through a sprocket wheel 39 and sprocket chain 40 to another sprocket wheel 41. This sprocket wheel and also a roller 42 are mounted rigidly upon an adjusting shaft 43. The pinion 41, collar 42 and adjusting shaft 43 all move bodily in relation to the rack 27, as above described, the direction of the movement being forward or backward according to the direction of the movement conferred upon the hand wheel 38.

A bearing 33^a is mounted upon the platform 21 and is rigid relatively thereto. Revolvably engaging this bearing is a threaded shaft 32^a provided at one of its ends with a

bevel gear 44 which meshes with another bevel gear 45 carried by a vertical shaft 46, the upper end of which has a hand wheel 47. The action of this hand wheel 47 and of the 5 parts just mentioned will be understood from the foregoing description of the action of the hand wheel 37 and parts connected with it. A hand wheel 48, a sprocket wheel 49 and a sprocket chain 50 are so connected 10 as to confer motion upon a sprocket wheel 51, a roller 52, and an adjusting shaft 53 substantially as already described with reference to analogous parts shown at the left of Fig. 1; that is to say, by turning the hand wheel 47 15 the adjusting shaft 53 may be moved in a direction lateral to its general length, and by turning the hand wheel 48 in another direction the adjusting shaft 53 may also be moved bodily in a direction crossing that of its axis. A strap 36^a is connected rigidly 20 with the platform 21, and within this strap and parallel with the platform 21 are racks 37^a of metal. Meshing with each rack is a pinion 38^a and these pinions together with 25 rollers 42^a are mounted upon opposite ends of an adjusting shaft 40^a. When this shaft is caused to rotate, the pinions 38^a move bodily along the racks 37^a, the rollers 42^a moving slidably along the strap 36^a. A 30 bearing 41^a is connected with the adjusting shaft 40^a and is threaded so as to fit upon the threaded shaft 32^a, one end of which shaft is mounted within the bearing 33^a fixed to the platform 21.

35 It will be noted therefore that the several adjusting shafts 30, 43, 53, 40^a are entirely independent of each other in their movements and consequently that the relative shifting of the suspenders 16, 17, 18, 19 is similarly independent. The result is that a variety of 40 adjustments may be given to the platforms 20, 21, and that the adjustments upon one of these platforms are entirely independent of the adjustments upon the other. For instance, referring to Fig. 1, the bottoms of the 45 suspenders 16 may be spaced widely from the bottoms of the suspenders 17, and the bottoms of the suspenders 18 may be likewise spaced widely from the bottoms of the suspenders 19. This causes the platforms 20, 21 to tilt in opposite directions when the platforms move to the right or left, as indicated in Fig. 4; thus a person sitting upon the seat 24 inclines forward at the instant when another person sitting upon the seat 25 inclines 50 backward. If now the adjusting shafts 30, 43, 53 and 40^a be moved by the action of the hand wheels into the position indicated in Fig. 5, neither of the platforms 20, 21 tilts 55 while the swing is in action, and consequently the seats 24, 25 maintain their relative positions.

Suppose now that the shafts 30, 43 be brought comparatively near together, and 60 similarly that the shafts 53, 40^a be brought

toward each other by the action of the hand wheels in the manner above described, and that the swing is again set in motion. The platforms 20, 21 now tilt in opposite directions as indicated in Fig. 6, and the degree of 70 inclination is somewhat greater than in other cases, yet the platform 20 tilts in a direction contrary to that of this same platform with the adjustments arranged as in Fig. 4, and the platform 21, as shown in Fig. 6, tilts in a 75 direction contrary to that of the same platform with the adjustments arranged as in Fig. 4.

It is obvious that as the movement of the adjusting shafts 30, 43, 53 and 40^a are entirely independent, either platform 20 or 21 can be caused to tilt either forward or backward for a given movement of the swing, and that the movement thus given is independent of the degree of adjustment and also of the 80 degree of tilting movement given to the other platform. For instance, the suspenders 16, 17 may be brought comparatively near together at their bottoms while the suspenders 18, 19 are spaced apart considerably at their 85 bottoms. In this manner any number of combinational movements may be given to the platforms, and the range of usefulness of the device is increased correspondingly.

I do not limit myself to any particular use 90 for the mechanism above described and especially to that part of the mechanism employed for adjusting the degree of inclination and the kind of inclination of the swinging platforms.

Having thus described my invention, I claim as new and desire to secure by Letters Patent:

1. The combination of a plurality of platforms, suspenders for supporting the same, mechanism connecting the said platforms together, and means controllable at will for varying the degree of inclination of one of said platforms independently of the other while said platforms are in motion.

2. The combination of a plurality of platforms, suspenders for supporting the same, a connection from one of said platforms to the other, and means controllable at will for adjusting said platforms relatively to said suspenders, for the purpose of varying the inclination of said platforms while in motion.

3. The combination of a frame, suspenders depending therefrom, a plurality of platforms mounted upon said suspenders and adapted to swing therewith, a connecting member extending from one of said platforms to another to maintain said platforms in unison with regard to their general swinging movement, and mechanism independent 120 of said connecting member for spacing said suspenders at different angles relatively to each other so as to vary the degree of inclination obtainable by the respective platforms while the latter are in motion.

4. The combination of a frame, suspenders depending therefrom, platforms mounted upon said suspenders and adapted to swing therewith, a connecting member extending from one of said platforms to another, so as to enable said platforms to swing in unison, and means controllable at will for spacing said suspenders at different angles relatively to each other for the purpose of causing said platform to incline while in motion.

5. The combination of a frame, suspenders depending therefrom, a platform supported by said suspenders, a rack and a pinion connected with said platform for varying the angular position of said suspenders relatively to each other for the purpose of causing said platform to tilt while in motion, and

means for turning said pinion relatively to said rack.

6. The combination of a frame, suspenders hanging therefrom, a plurality of separate platforms supported by said suspenders and adapted to tilt, a connection from one of said platforms to another, and means controllable at will for adjusting the tilting of one of said platforms independently of the other while said platforms are in motion.

In testimony whereof I have signed my name to this specification in the presence of two subscribing witnesses.

CHARLES FRANK BEAN.
